UNITED STATES PATENT OFFICE.

HARRY M. ROSENBLATT, OF PHILADELPHIA, PENNSYLVANIA.

DESIGN FOR A BICYCLE-SADDLE FRAME OR BASE.

SPECIFICATION forming part of Design No. 31,598, dated October 3, 1899.

Application filed July 27, 1899. Serial No. 725,330. Term of patent 7 years.

To all whom it may concern:

Be it known that I, HARRY M. ROSENBLATT, a citizen of the United States, residing at Philadelphia, county of Philadelphia, and State of Pennsylvania, have invented and produced a new and original Design for a Bicycle-Saddle Frame or Base, of which the following is a full, clear, and exact description, reference being had to the accompanying drawings, which form a part of this specification.

My invention relates to a metallic frame or base for bicycle-saddles which is ordinarily faced with leather and padded with felt or other material.

15 The object of the invention is to produce a novel form of base or frame adapted to receive the supporting-bars.

It consists of the frame representing the features illustrated in the drawings and hereinafter described.

20 In the drawings, Figure 1 is a plan view of the saddle frame or base. Fig. 2 is a section on line 2 2 of Fig. 1, and Fig. 3 is a rear view.

25 The design consists in a rigid metal saddle frame or base of general lenticular form, having the wide rear portion and the narrow front

portion or nose, the sides or edges of which merge into the rear portion, there being three supporting-bar-engaging clips struck or bent 30 down from the body of the frame and projecting from the under surface of the frame, two of which *a* and *a'* are at the rear of the frame at points equidistant from an imaginary line bisecting the frame longitudinally, while the 35 third clip *b* is located toward the front of the saddle and extends longitudinally along said imaginary line. These clips and their relative arrangement with respect to each other and the body of the frame form the leading 40 feature of the design.

Having now fully described my invention, what I claim, and desire to protect by Letters Patent, is—

The design for the base or frame of a saddle for bicycles, substantially as shown.

In testimony of which invention I have hereunto set my hand, at Philadelphia, Pennsylvania, on this 24th day of July, 1899.

HARRY M. ROSENBLATT.
